Primary Examiner—Caron D. Veynar*Assistant Examiner*—Garth Rademaker(57) **CLAIM**

The ornamental design for a geometrical vase, substantially as shown and described.

DESCRIPTION

FIG. 1 is a perspective view of a geometrical vase showing my new design;

FIG. 2 is a bottom plan view thereof;

FIG. 3 is a top plan view of FIG. 1; and,

FIG. 4 is a side elevational view of FIG. 1, the opposite side being a mirror image thereof.
